Application November 21, 1930
Serial No. 497,103

9 Claims. (Cl. 229—6)

The present invention has relation to the manufacture of boxes of a particular type and while the invention is especially applicable in the manufacture of cigar boxes, the invention may also be applied with advantage to boxes used for packing and displaying other kinds of merchandise.

The invention will be hereinafter described in connection with the manufacture of cigar boxes or other cases where certain special requirements have to be filled. Heretofore cigar boxes have generally been made of wood because the first requirement in packing of cigars is a rigid box so that the cigars may be safely shipped or handled without danger of being crushed. Another requirement is the distinctive appearance of the box because since the trade has become accustomed to the use of wooden cigar boxes for a great many years it might be difficult to substitute paper boxes unless the box made of paper has the features of a wooden box. Heretofore cigar boxes have been made partly of wood and partly of paper board and various methods of manufacture have been employed. Such boxes have apparently not satisfied the demand for the special box required for cigars and it is the main purpose of the present invention to produce a box made entirely of paper board which will meet all the requirements for a practical cigar box.

In common practice folding and set up boxes of all kinds are made entirely of paper board and said board is of different gauge from the very light weight to comparatively heavy board. Furthermore, in the manufacture of boxes made of paper board it is customary to score or crease the board where it is to be bent or in some instances, the board is partly cut at the bending point so as to permit of the bending without breaking the board. It is proposed, according to this present invention, to use extra heavy board ordinarily incapable of being bent without breaking and the purpose of using this heavy board is to meet one of the requirements for cigar boxes, viz, a rigid box.

In carrying out the invention the paper board used may be of ordinary stock but to get the full advantage of the invention, the stock is composed of laminated sheets of which the outer or top lamina or laminae is composed of comparatively tough material and the inside laminae are of a common stock kind which is more or less deficient of fiber. Other kinds of board may be employed provided the outer surface has sufficient tensile strength to permit it to stand the bending operation without breaking.

In the manufacture of the improved box, the board is blanked out into sheets from which the box is ultimately made up. Various alternative methods of carrying out the invention will be hereinafter described and in each example or embodiment of the invention the blank is divided into a number of sections by a cut score or groove at the point where said blank is folded to form the walls of the box body. These grooves or scores are cut partly through the stock, that is, up to the outer lamina or covering of the top surface of the board and the uncut portion acts as a hinge on which the various sections are bent to form the walls of the box body or frame forming the base for the box. The cut scores may be on either side of the board depending whether or not the sections fold inwardly or outwardly and when the sections fold inwardly, said cut scores are preferably V-shaped so that the edges will come together with a mitre fit but where the sections fold outwardly the cut is straight through the board up to the binding or surface lamina. When the blank is folded to form said box body or frame the corners of said body are held together and reinforced by strips or stays which are preferably secured by adhesive means. The next operation is to add a covering shell preferably composed of foldable paper board which may be of superior quality. Said board may be printed or otherwise decorated to represent different kinds of wood, for example. This covering may be on the outside of the box only, but if desired, a similar lining may be applied to cover the inside of the box.

The box body built up, as above described, is then ready for the final finish and this usually is the application of binding of the usual strip or webbing commonly employed in the manufacture of cigar boxes. It will be understood that the lining may be applied to the box body not only for decoration purposes but as a strengthening means. An outer wrapper is generally employed to cover the complete outside surface of the box and which wrapper may be suitably printed and decorated.

The improved method of manufacturing the box briefly outlined above and more fully described hereinafter has the advantage that boxes made by this method are produced with greater facility, more economically and the box is strengthened to the maximum degree obtainable with the material employed and the appearance of the box is greatly improved.

The several embodiments of the invention will be hereinafter described with reference to the accompanying drawing, wherein—

Figure 1 is a perspective view showing the invention as applied to a cigar box;

Figure 2 is a detail view of the frame member of the box body; and

5 Figure 3 is a perspective view showing a separate member forming the shell or covering for the box body.

Referring to the embodiment illustrated in said drawing the box body 1 is of a rectangular shape 10 having a front wall 2, back wall 3 and end walls 4-5. Following the usual practice, in making a cigar box, the end walls 4-5 are slightly higher than the front and back walls so as to provide a recess 6 to receive the cover 7 when in a closed 15 position, so that the top surface of the cover will lie flush with the upper edges of the side walls 4-5. The purpose of this fitting of the cover is to ensure a tight closure and to stiffen the box structure. The box body is composed 20 of several members or parts of which the main member is the frame 8 composed of heavy, non-bendable paper board. This frame may be in the form of a strip which is divided into sections by cut score lines 9, said sections being numbered 25 2', 3', 4', 5' forming respectively the front, back and end walls of the structure. The board preferably employed is of such a thickness and weight that the box produced therewith is equally as rigid as the boxes heretofore made of wooden 30 strips or panels. The paper board employed may be composed of laminated sheets or the board may have a pressed paper pulp filler which is covered by a paper sheet 10 on one side and sheet 11 on the other side. The covering sheet 10 35 should be of comparatively tough material so as to hold the frame together in its set up position for it will be understood that the sections, when folded, are hinged on the uncut surface sheet 10. The cut 9, it will be understood, in one form is 40 cut through the outer covering sheet 11, through the filler but the inner sheet 10 is not cut. It will be noted when so prepared the folded frame presents neat and unbroken corners on the inner side of the box but on the outside, in folding, 45 angular grooves are left but which latter are covered in a manner hereinafter set forth.

As hereinbefore stated, the frame 8 of the box body may be composed a continuous strip and when the frame is formed, the two ends of the 50 strip are brought together with a butt joint, as shown at 12, and a stay piece 13 is adhesively secured preferably on the outside to hold the ends together. In order to keep the front and side walls perfectly parallel to each other to provide 55 a squared box structure, the end wall section 5' is of a greater length than the opposite section 4' so that the butt joint referred to may be employed.

Another component part of the box body is a 60 shell 14 as shown in Figure 3 of the drawing. This shell 14 is composed of box board of the usual kind employed for making folding boxes. This board is cut out in the form of a blank having sections 2'', 3'', 4'', 5'' which form reinforcements or coverings respectively for the back, 65 front and end walls of the structure. The shell 14 has the central section 15 which constitutes the bottom of the box when said shell is located in its operative position with relation to the open frame 8. When this shell is located in place 70 the corners are united and retentively held by corner stays in the usual manner followed with the manufacture of set up boxes.

The body of the box having been formed by 75 the assembling of the frame 8 and shell 14, the

box body is then ready to be finished in the customary way by covering the same with a printed or decorated wrapper 16. The outer shell 14 may, however, be printed or decorated directly so as to represent cedar wood, for example, and the corners and edges of the box body may be covered by a binding web in the usual manner. 30

It will be obvious with the embodiments of the invention hereinbefore described, that the hinges or cut scores 9 of the frame 8 may be inside of the box structure and in which case the cuts would be in the form of V-shaped grooves so as to produce a mitre joint. With this modification the reinforcing shell may be placed inside of the set up frame 8 for it will be understood that when the frame 8 is folded as in this example, the outer corners of the structure are not broken. 85

Various modifications may be made in carrying out the constructional details of the invention or in the application of the same other than hereinbefore described and it is therefore to be understood any modification coming fairly within the terms of the appended claims shall be covered thereby. 90

I claim:

1. A cigar box comprising a body composed of an open frame of relatively heavy stiff paperboard forming the side walls of the box and an outer shell of tough bendable paper material providing the bottom for the box and a covering for 100 said frame. 105

2. A cigar box comprising a body composed of an open frame of stiff paperboard forming the side walls of the box, an outer shell of tough flexible paper material providing the bottom 110 for the box and a covering for said frame, and an inner shell providing a lining and re-enforcement for said side walls and bottom. 110

3. A box of the class described comprising a body composed of an open frame of heavy stiff 115 paperboard forming the side walls of the box, an outer shell of tough bendable paperboard providing the bottom for the box and a covering for said frame, an inner shell providing a lining and re-enforcement for said side walls and bottom, 120 and means comprising corner strips for retaining said outer shell in the set up or operative position. 120

4. A box of the class described comprising a frame having an open top and bottom, said frame being composed of a strip of heavy stiff paperboard having the ends united and scored so as to fold to form the end and side walls of the box, an outer shell having folding sections providing the bottom of the box and covering panels for said end and side walls, and a wrap sheet covering said 130 outer shell. 130

5. In the manufacture of boxes of the class described, a base or frame for the box composed of a strip of stiff paper board cut and creased to define sections forming the side and end walls of the box, said strip having ends united to form said frame, an outer shell of tough bendable paperboard having sections covering said end and side walls and providing a bottom for the box, and an inner covering providing a re-enforcing lining 140 for the side, end and bottom walls of the box. 140

6. A box body, including side and end walls in the form of a frame composed of non-bendable paper board stock having a relatively tougher surface lining or lamina, and previously prepared by scoring or grooving to provide sections forming the walls of the frame, which scoring or grooving extends in a depth approximately up to the lining or lamina, and an outer shell composed of bendable paper board covering one of the up- 145 150

right surfaces of the frame, and having a central section forming the bottom of the frame, whereby the box body is completed.

7. A box body, including side and end walls in the form of a frame composed of solid, non-bendable paper board stock having a relatively tougher surface lining or lamina and previously prepared by scoring or grooving to provide sections forming the walls of the frame, which scoring or grooving extends in a depth approximately up to the lining or lamina, and an outer shell composed of bendable paper board snugly covering one of the upright surfaces of the frame, and having a central section forming the bottom of the frame, whereby the box body is completed.

8. A cigar box comprising a body including a frame of relatively stiff paperboard material

forming the side walls of the box, a corner stay glued to said side walls securing the same in assembled relationship, an outer shell of tough strong paper material providing a bottom for the box and a covering for the frame, and a wrap sheet covering said outer shell.

9. A cigar box comprising a body including a frame of relatively stiff paperboard material forming the side walls of the box, an outer shell of tough flexible paper material having bottom and side wall portions within which said frame is positioned, corner stays glued to the side wall of said outer shell maintaining the same in assembled set up relationship, and a wrap sheet completely covering said outer shell.
